(57) **CLAIM**

What is claimed is an ornamental design for a wireless charger and power bank, as shown and described.

DESCRIPTION

FIG. 1 is a front, top, and left side perspective view of a wireless charger and power bank showing our new design; FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof; and,

FIG. 8 is a front, top and right side perspective view shown in an exemplary embodiment of use, namely, wirelessly charging a watch and mobile phone.

The broken lines shown in the drawings are for the purpose of illustrating portions of the wireless charger and power bank that form no part of the claimed design. The broken lines showing the watch and mobile phone elements in FIG. 8 are for the purpose of illustrating environmental structure and form no part of the claimed design.
